UNITED STATES PATENT OFFICE.

WILLIAM MAVER, JR., OF JERSEY CITY, NEW JERSEY.

MULTIPLE TELEGRAPHIC REPEATER.

SPECIFICATION forming part of Letters Patent No. 339,449, dated April 6, 1886.

Application filed April 22, 1885. Serial No. 163,063. (No model.)

To all whom it may concern:

Be it known that I, WILLIAM MAVER, Jr., a citizen of the United States, residing in Jersey City, in the county of Hudson and State 5 of New Jersey, have invented certain new and useful Improvements in Multiple Automatic Telegraph-Repeaters, of which the following is a specification.

The invention relates to the class of apparatus employed for repeating into one electric circuit the messages or signals transmitted over another electric circuit.

The object of the invention is to provide means automatically controlled for repeating from any one of a given series of conductors into any or all of a second series, and vice versa. This organization of apparatus involves the possibility of at any time signaling back from any one of the receiving series of 20 lines or conductors to the line from which the signals are being repeated.

The invention consists, generally, in so organizing the apparatus at the repeating-station that a current coming over any one of 25 either series of lines will control the connections of a corresponding local circuit in which there is included an electro-magnet serving in its turn to control the connections of a corresponding second local circuit. In each of 30 these second local circuits there is included a repeating-magnet. The one series of repeating-instruments serves to control the connections of the main-line batteries applied to the respective lines of the series controlling the 35 other series of repeating-instruments, and vice versa.

The electro-magnets mentioned as controlling the local-circuit connections for the repeating-magnets are employed for the especial 40 purpose of reversing the signals as received from the transmitting-lines, and may be termed "reversing-magnets." These may, however, be dispensed with by placing the series of repeating-magnets in the first-named local circuit. 45 By making and breaking the connections of any one of either series of lines at a transmitting-station signals will be repeated into each of the other series of main lines. If, however, a receiving operator of the one series desires 50 to break in upon and to signal back to the transmitting operator, an interruption of the circuit at his station will cause the reversing-

magnet applied to the corresponding series to interrupt the circuit of the main line from which the message is being repeated, and a 55 signal will then be given to the transmitting operator. As already stated, the reversing-magnets may be dispensed with, but usually they are preferred for the purpose of rendering it possible to readily adapt the existing 60 apparatus to this system.

For the purpose of preventing the relay-instruments of either series of lines from operating the series of repeating instruments of the other series of lines in response to the 65 movements of their levers, occasioned by the repeated signals, a circuit-interrupting device is applied to one of the repeating-instruments of each series, whereby the connections of the local circuit employed for actuating the repeaters of the transmitting-lines are kept from 70 being completed while the receiving-repeaters are in operation.

I am aware of the existence of other multiple repeaters, such for instance as described 75 in the patents of Smithers, Nos. 268,561 and 279,670; Ballou, No. 250,774, and Gally, No. 158,927.

In the accompanying drawings, Figure 1 is a diagram of the general organization of apparatus at the repeating-station. Fig. 2 represents the modification in which the reversing-magnets are dispensed with at the repeating station.

Referring to Fig. 1, two series of main lines 85 are shown, each series being three in number in this instance, the conductors L' , L^2 , and L^3 constituting the first series, and the conductors L^4 , L^5 , and L^6 the second series. These series may, however, be indefinitely extended, 90 as will hereinafter appear. It is designed that the movements of the transmitting-keys which are applied to these two series of lines, respectively, shall control the movements of one or the other of two reversing-magnets, R' and R^2 , respectively, accordingly 95 as the key belongs to one or the other of the two series of lines. The coils of the electro-magnets R' and R^2 are respectively included in the circuits of local batteries o' and o^2 . Included in each of the main-line conductors there is a relay-magnet, as shown at r' , r^2 , and r^3 , and r^4 , r^5 , and r^6 . The main line L' leads from the coils of the electro-magnet r' to one 100

5 pole of a main-line battery, O' , in a manner which will be hereinafter described. The remaining pole of this battery is connected through a conductor, l , with a conductor, l' , leading to the earth at g' . In like manner the conductors L^2 and L^3 are connected through the coils of the electro-magnets r^3 and r^4 , with the poles of the main-line batteries O^2 and O^3 , the remaining poles of which are connected 10 through conductors 2 and 3, respectively, with the conductor l' , and thus with the earth. It is evident that a single battery might be placed in the conductor l' , in place of the separate batteries in the conductors 1, 2, and 3.

15 One pole of the local battery o' , which has been referred to, is connected with the respective armature-levers a' , a^2 , and a^3 of the relay-magnets r' , r^2 , and r^3 . The front contact-stops, b' , b^2 , and b^3 of the armature-levers are insulated, 20 while the back contact-stops, c' , c^2 , and c^3 , are all connected through a conductor, 8, in a manner which will be hereinafter described, with a conductor, 9, leading to one terminal of the coils of the reversing-magnet R' . The remaining 25 terminal of these coils is connected through conductor 11, with the remaining pole of the battery o' . When therefore the main-line connections of all the first series of lines are complete, the armature-levers a are in their forward positions, and the circuit of the battery o' is interrupted. The armature-lever d' of the reversing-magnet R' , therefore, rests against its back contact-stop. By interrupting the connections of any one of the main 30 lines of the first series the corresponding armature-lever will fall back, and thus complete the connections of the battery o' . The armature-lever d' will thereby be drawn forward.

40 Normally, the circuit of the battery o' being interrupted, the lever d' rests against its rear contact-stop, e' , and thereby completes the circuit-connections of a battery, p' , one pole of which is connected by the conductor 12 with 45 the contact-stop e' , while the other pole is connected through the coils of a series of repeating-magnets, K' , K^2 , and K^3 , and with the armature-lever d' by a conductor, 13. As long, therefore, as the circuits of the main line L' , 50 L^2 , and L^3 are complete the circuit of the battery p' will also be complete, and the armature-levers k' , k^2 , and k^3 will be drawn into their forward position, as shown in the drawings. When, however, the connections of any one of 55 the main lines are interrupted, then the armature-lever d' being drawn away from its point e' , the electro-magnets K' , K^2 , and K^3 will be demagnetized, and the corresponding armature-lever will fall away. The movements of 60 the armature-levers k' , k^2 , and k^3 thus occasioned serve to make and break the circuit-connections of the main-line batteries O^4 , O^5 , and O^6 , which are applied to the second series of lines, L^4 , L^5 , and L^6 , respectively, and which 65 correspond to the batteries O^4 , O^5 , and O^6 . To this end the battery O^4 has one pole connected with a contact-point, f' , which is preferably

applied to an insulated contact-spring, h' , carried upon the armature-lever k' . This spring is in turn connected by a conductor, 14, through 70 the coils of the electro-magnet r^4 , and thus with the main line L^4 . The remaining pole of the battery O^4 is connected by a conductor, 4, with the conductor l' , leading to the earth at g^2 . It will be observed, therefore, that the 75 movements of the armature-lever k' in response to the movements of the armature-lever d' will serve to make and break the connections of the battery O^4 in a manner corresponding precisely to the completions and interruptions of the connections of the main line L' , L^2 , or L^3 .

80 The battery O^5 has one pole connected with the contact-point f^2 , and the battery O^6 has a corresponding pole connected with the stop f^3 . The stops f^2 and f^3 are respectively applied to the levers k^2 and k^3 , and these levers are connected by conductors 15 and 16, respectively, through the coils of the relay-magnets r^5 and r^6 with the main lines L^5 and L^6 . 90

95 It will be readily understood from the foregoing description that any signals which are transmitted upon any one of the main lines L' , L^2 , and L^3 , constituting the first series, will be thus retransmitted by currents from the batteries O^4 , O^5 , and O^6 into all of the second series of lines L^4 , L^5 , and L^6 , respectively.

100 It will be observed that the interruptions of the circuits of the batteries O^4 , O^5 , and O^6 which are thus occasioned will cause the armature-levers a^4 , a^5 , and a^6 of the relay-magnets r^4 , r^5 , and r^6 to fall backward against their rear contacts, b^4 , b^5 , and b^6 , respectively. These contacts are connected through conductors 17 and 18 with the coils of the second reversing-magnet, R^2 , and they serve to perform the same 105 functions as the armature-levers a' , a^2 , and a^3 . They would therefore serve to operate the reversing-magnet R^2 when a message is being transmitted from the first series of main lines, 110 unless some means were provided to obviate this difficulty. One pole of the battery o^2 is connected with the armature-levers a^4 , a^5 , and a^6 by conductors 19, 20, and 21, while the remaining pole is connected with the conductor 115 18 by a conductor, 22, leading through the coils of the reversing-magnet R^2 . It is necessary, therefore, that the circuit of the battery o^2 should be interrupted at some other point before it is completed by the falling of any 120 armature-lever a^4 , a^5 , and a^6 away from its front contact-stop, c^4 , c^5 , or c^6 , against its back stop, b^4 , b^5 , or b^6 . For this reason the conductor 17 preferably leads to a contact-stop, j' , applied 125 to a contact spring or extension, n' , carried upon the armature-lever k' . This spring is in connection through the armature-lever with the conductor 18, leading to the reversing electro-magnet R^2 . When the armature-lever k' is in its forward position, as shown in 130 the drawings, the conductor 17 is thus connected through the contact-stop and spring with the conductor 18; but by the movement of the armature d' of the reversing-magnet R'

135

the circuit of the battery p' is interrupted, and likewise the circuits of the batteries O' , O^5 , and O^6 , causing the armature-levers a^4 , a^5 , and a^6 to fall against their back-contact stops; but 5 the connection between the conductors 17 and 18 is also interrupted, so that the circuit of the battery o^2 remains incomplete.

The reversing-magnet R^2 serves, in response to the movements of the keys applied to the 10 lines L' , L^5 , and L^6 of the second series, to control the movements of the armature-levers k^4 , k^5 , and k^6 of the electro-magnets K^4 , K^5 , and K^6 . These last magnets are employed for repeating 15 from the first series to the second series of main lines. The electro-magnet K^4 corresponds precisely to the electro-magnet K' , and likewise the magnets K^5 and K^6 correspond to the magnets K^2 and K^3 , and a detailed description is therefore unnecessary.

20 The movements of the lever d^2 of the reversing-magnet R^2 serve to control the circuit-connections of a local battery, p^2 , corresponding to the battery p' . The armature-levers k^4 , k^5 , and k^6 respond to the movements of the armature-lever d^2 , and repeat from the batteries 25 O' , O^5 , and O^6 into the lines L' , L^5 , and L^6 .

It frequently occurs that during the signalling from one line through a repeating-instrument into a second line it is necessary for the 30 receiving operator to communicate back to the transmitting operator—as, for instance, when it is desired that some portion of the message be retransmitted. To accomplish this, it will be necessary only for the receiving operator 35 to employ his key in the usual manner. Considering that the operator upon the main line L' is transmitting, and that the operator upon the line L^6 wishes to communicate with the transmitting operator, then, by the interruption 40 of the main line L^6 at the receiving-station the armature-lever a^6 of the magnet r^6 will be allowed to fall back against its rear contact-stop b^6 . The circuit of the battery o^2 will then be completed through the coils of 45 the reversing magnet R^2 , the conductor 18, armature-lever k' , stop j' , conductor 17, contact-stop b^6 , lever a^6 , and conductor 21. Should the armature k' chance to be away from its electro-magnet at the moment the circuit of 50 the line L^6 is interrupted, then the circuit of the battery o^2 will not be completed until the armature-lever of k' is returned to its forward position, which it is evident it will do immediately upon the transmission of a signal from 55 the line L' . The circuit of the battery o^2 being thus completed, the armature-lever d^2 will be drawn forward, interrupting the circuit of the battery p^2 , thereby causing all the armature-levers K^4 , K^5 , and K^6 to fall back and interrupt 60 the circuits of the batteries O' , O^5 , and O^6 . The movements of the key of the transmitting operator upon the line L' will therefore produce no effect upon the instrument at his station, and he will thus be notified that some one of the receiving operators desires to communicate back. 65 The operator upon the line L^6 is then enabled to transmit as follows: The line from the main

line L^6 is complete through the conductor 16 to the armature-lever k' , thus to the battery O^6 , and from the battery to the earth through 70 the conductor l^2 . The movements of the lever a^6 in response to the movements of the key included in the line L^6 cause the circuit of the battery o^2 to be made and interrupted, and the signals to be retransmitted through 75 the line L' in a manner readily understood.

It should be here noted that one essential feature of a repeating apparatus is that it should be so organized that by no possible act can the various parts come into such position 80 that it is impossible to complete the circuit-connections from any one of the main lines. It is evident that this end is attained in the present instance, for, as has already been shown, the circuit of the battery p' must be 85 closed before the circuit of the battery p^2 can be interrupted, and vice versa; but if by any chance the circuits of both batteries p' and p^2 should become interrupted at the same time immediately the corresponding reversing-instrument, R^2 or R' , will serve to again complete the connections, for the reason that the circuit of the battery o' or o^2 will be interrupted at the point j' or j^2 , thereby causing the armature-lever d' or d^2 to fall against its 95 back contact-stop, and to complete the connections of the corresponding battery, p' or p^2 .

In Fig. 2 a modification is shown in which the reversing-magnets R' and R^2 are dispensed with. In this instance the relay-magnets K' , K^2 , and K^3 are included in the circuit of the battery p' , while the corresponding magnets, K^4 , K^5 , and K^6 , are included in the circuit of the battery p^2 . The circuits of these batteries being open when the main-line connections 105 are complete, the levers k will be away from their electro-magnets, and the parts are so organized that the respective circuits of the batteries O will be completed through the rear contact-stops of these levers. 110

A circuit-connection may be completed from the conductor leading to the back contact-stops to the front contact-point of one or more of the relay-magnets and a sounder included therein, as shown in dotted lines, for the purpose of affording opportunity for the messages to be read at the repeating-station. The same local battery will, it is evident, serve to operate this sounder. 115

It is evident that a single repeater may be 120 operated upon this principle without departing from the spirit of the invention, a transmitter and a relay being employed for each main-line circuit, each transmitter being organized to break the local circuit of the other 125 before the main-line circuit-connections are interrupted, so that each transmitter will be kept idle while the other is being operated.

I claim as my invention—

1. The combination, substantially as hereinbefore set forth, with two series of main-line conductors, of a source of electricity applied thereto, and means, substantially such as described, for automatically repeating from 130

any line of either series into all of the lines of the other series.

2. The combination, substantially as hereinbefore set forth, with two series of main lines, 5 of a repeating-magnet applied to each of said lines, means for automatically operating the repeating-magnets of either series by currents from any one of the lines of the other series, and means, substantially such as described, 10 whereby the operation of one series of repeating-magnets temporarily prevents the operation of the other series.

3. The combination, substantially as hereinbefore set forth, of two series of lines, two 15 series of repeating-magnets, means for repeating from any line of either series into all the lines of the other series, means, substantially such as described, whereby the operating-repeaters prevent the other repeaters from 20 operating, and means, substantially such as described, whereby a receiving-line prevents the operation of its repeater at the completion of a signal.

4. The combination, substantially as hereinbefore set forth, of a main line, a relay-magnet included in the circuit thereof, a battery the connections of which are made and interrupted by the movements of the key applied to said main line, a reversing-magnet, a 25 battery applied thereto, the circuit-connections of which are made and interrupted by the operation of said relay, and a series of repeating-instruments, all of which are controlled by the operation of said reversing-instrument.

35 5. The combination, substantially as hereinbefore set forth, of two reversing-instruments, two series of main lines respectively corresponding to said instruments, means, substantially such as described, operated by 40 currents traversing said main lines for operating said instruments, and means, substantially such as described, for normally preventing one of said instruments from operating while the other instrument is in use.

45 6. The combination, substantially as hereinbefore set forth, of two series of lines, two reversing-instruments respectively corresponding thereto, means for operating either of said instruments by currents traversing one 50 of the lines of the corresponding series and for preventing one of said instruments from operating while the other is in use, and means for interrupting the operation of the first instrument and bringing the second into operation at the termination of a signal.

55 7. The combination, substantially as hereinbefore set forth, with a telegraphic main line, of an electro magnet included therein, a series of lines, a battery for applying currents 60 to said series of lines, a local battery and its circuit, the connections of which are controlled by said electro-magnet, an electro-magnet included in said circuit, and a series of circuit-controlling magnets applied to series of lines, 65 respectively, and controlled by the operation of the last-named electro-magnet.

8. The combination, substantially as here-

inbefore set forth, with a series of main lines, of a reversing-instrument, means, substantially such as described, for actuating the same, a 70 local battery, its circuit, the connections of which are controlled by said reversing-magnet, armature-levers respectively applied to electro-magnets and serving to control the connections of the series of main lines, respectively, 75 a second reversing-instrument, a local circuit for operating the same, and means, substantially such as described, applied to one of said series of electro-magnets, whereby the circuit-connections of said second local battery may 80 be interrupted when the circuit of said first-named local battery is interrupted.

9. The combination, substantially as hereinbefore set forth, of the main-line battery O', and the electro-magnet r', its armature and 85 rear contact-point, the local battery o', the reversing-magnet R', included in the circuit of said local battery, a main line, the local battery p', the circuit-connections of which are controlled by the operation of the repeating-magnet R', the series of electro-magnets included in the circuit of said battery p', and the series of main lines having their circuit-connections controlled by the armature-levers of said series of electro-magnets, respectively. 95

10. The combination, substantially as hereinbefore set forth, of a main line, a battery, an electro-magnet included in the main-line circuit, its armature and rear contact-point, the local battery o', the circuit-connections of which are controlled by the operation of said electro-magnet, the series of electro-magnets controlled by the opening and closing of the circuit of said local battery, a series of main lines having their circuit-connections controlled by the armature-levers of said series of electro-magnets, respectively, a second local battery having its circuit-connections substantially the same as those of the first-named local battery, and means, substantially such as 105 described, for preventing the second local circuit from being completed by the operation of the first-named electro-magnet.

11. The combination, substantially as hereinbefore set forth, of the instruments R' and 115 R², the two series of instruments K', K², and K³, and K⁴, K⁵, and K⁶, means, substantially such as described, for operating the instruments R' and R², and thereby controlling the movements of the two series of instruments, 120 respectively, and two series of main lines, the connections of which are controlled by the respective armatures of said series of electro-magnets.

12. The combination, substantially as hereinbefore set forth, with two independent series of telegraphic main lines, of means for repeating from any line of one series into the other series of lines, and means, substantially such as described, whereby signals may be automatically transmitted from any of the last-named series of lines back into the first-named line. 125

13. The combination, substantially as here-

inbefore set forth, of two series of lines, a relay-magnet included in the circuit of each of said lines, two series of repeating-instruments respectively applied to the lines of said series, 5 two local batteries respectively controlled by any relay of the corresponding series, and two circuit-controlling devices respectively controlled by the local batteries, whereby during the operation of a relay belonging to 10 one series of lines the repeating-instruments of that line are prevented from operating.

14. The combination, substantially as hereinbefore set forth, with two independent series of main lines, of a transmitter, a reversing-magnet, and a relay for each series, a local cir- 15

cuit for each reversing-magnet, each transmitter being arranged to break the local circuit of the reversing-magnet of the other transmitter before the main-line circuit is broken, whereby one transmitter is inoperative while 20 the other is being operated, substantially as described.

In testimony whereof I have hereunto subscribed my name this 20th day of April, A. D. 1885.

WILLIAM MAVER, JR.
